UNITED STATES PATENT OFFICE.

CHARLES L. STUBBS, OF AKRON, OHIO.

TILE.

Application filed February 25, 1924. Serial No. 694,886.

The present invention relates to tile or brick, and has for its object to provide an object of this character which embodies novel features of construction, whereby adjacent or superposed rows of the tile or brick will be held in a properly spaced relation so that mortar or cement can be caused to flow or be distributed uniformly between the same.

Further objects of the invention are to provide a brick or tile of this character which is comparatively simple and inexpensive in its construction, which can be handled in the same way as ordinary tile or brick, and which may also be provided with means for obtaining a firm bond with underlying cement or mortar.

For a fuller understanding of the invention reference is to be had to the following description and accompanying drawings, in which,

Figure 1 is a perspective view of a tile which is constructed in accordance with the invention.

Figure 2 is a bottom plan view of a slightly modified form of tile.

Figure 3 is a similar view showing a further modification.

Figure 4 is a view of several adjacent rows of the tile which have been loosely assembled, showing the manner in which the side lugs of the tiles operate to hold the tiles of adjacent rows in a uniformly spaced relation.

Figures 5 and 6 are plan views showing further modifications of the invention.

Figures 7 and 8 are views of the opposite sides of a tile showing another modification of the invention.

Corresponding and like parts are referred to throughout the following specification and indicated on all of the views of the drawings by like reference characters.

On all of the various figures of the drawing the reference character A designates the body portion of a tile which may be of any conventional size or shape, and may be formed of any suitable material. The tiles are ordinarily rectangular in shape, substantially as illustrated, and such tiles can be readily assembled in adjacent rows when using them as a facing for a floor or wall, either for interior or exterior work. The tile A of Figure 1 is shown as provided at the back thereof with a pair of diverging wings 1, which have a width corresponding

to that of the tile and are adapted to be embedded in the cement or other plastic material so as to obtain a firm bond between the tile and the said cement. One face of the tile is provided with a series of laterally projecting spacing lugs 2 which may be of any desired shape, and if desired, the edges of the wings 1 may also be provided with lugs 2. When the tiles A are assembled in a series of adjacent rows, as indicated by Figure 4, the lugs 2 projecting from the tiles of each row will engage the tiles of an adjacent row, so that the several rows of tile will be held in a properly spaced relation. This assures a uniform and even spacing between adjacent rows of the tiles and, if desired, the tiles can be loosely assembled in this manner and the plastic cement or mortar poured between the same.

A slight modification is shown by Figure 2, in which the back of the tile is provided with a dove-tail shaped projection 1^a which is adapted to become firmly interlocked with a cement or mortar backing and cause the tile to be firmly anchored in place.

Figure 3 illustrates a further slight modification in which the back of the tile is provided with a substantially cylindrical projection 1^b which has an opening 2^b extending axially through the same. This member 1^b will become embedded in the cement or plastic material used as a backing for the tile and the plastic material will also enter the opening 2^b, so that the tile will be firmly anchored or bonded in position.

Figure 5 shows a further modification in which the rear face of the tile is provided with a dove-tail shaped recess 1^c. The cement or plastic material used as a backing for the tile will enter this recess and become interlocked with the undercut sides thereof, with the result that the tile will be firmly bonded or anchored in position.

In the modification shown by Figure 6 the back of the tile is provided with a knob 1^d which is connected thereto by a reduced neck portion 3. This knob will embed itself in the cement or plastic material which is used as a backing for the tile and interlock therewith so that the tile will be securely bonded in position.

All of the different forms of the invention which have thus been described are provided, the spacing lugs 2 projecting from one side of the tile, so that when the tiles are assembled in adjacent or superposed rows, as in

dicated by Fig. 4, the adjacent rows will be held in a uniformly spaced relation. This insures a uniform spacing of the tiles and also enables the tiles to be loosely assembled and the cement or mortar poured in between the same.

A further modification is illustrated by Figures 7 and 8, in which one side of the tile is provided with a longitudinally extending groove 5 and the other side of the tile is provided with a pair of spacing lugs 6. The spacing lugs 6 and the groove 5 are both arranged at the same distance from the front of the tile, and the lugs 6 of the tiles in one row are adapted to engage the grooves 5 of the tiles in an adjacent row. The faces of the tiles are thus held properly in the same plane, so that the exposed face of the tiled wall or floor will be perfectly flat and smooth. The length of the lugs 6 is greater than the depth of the groove 5 by an amount equivalent to the spacing which it is desired to maintain between adjacent rows of the tiles. The lugs 6 thus cooperate with the grooves 5 to hold the faces of the tile in the same plane and also to hold the tiles in a spaced relation, just as in the previous instance.

The tile of Figures 7 and 8 may also be provided with suitable means such as the wings 1^a for bonding the tile to a plastic backing material, and these wings may also be provided with spacing lugs 2, as in Fig. 1, if this is desired.

While certain preferred forms of the invention have been illustrated and described

in detail, it will be understood that there are many other modifications and changes which can be made in the shape, design and details of the tile without departing from the spirit of the invention.

Having thus described my invention what I claim as new and desire to secure by Letters Patent is,

1. A building brick including a substantially rectangular body member, a rearwardly extending anchoring lug at the back thereof, said lug being shorter than the brick and extending the full thickness thereof so that the upper and lower faces thereof are flush with the top and bottom of the brick, spacing lugs projecting from the bottom of the brick and adapted to engage an underlying brick to hold the bricks a predetermined distance apart, and a corresponding spacing lug projecting from the anchoring lug and adapted to cooperate with the before mentioned spacing lugs to maintain the desired spacing between superposed rows of bricks.

2. A building brick including a substantially rectangular body member provided with a rearwardly projecting anchoring lug which is shorter than the brick and is formed with an opening extending transversely to the brick, said anchoring member being adapted to interlock with the plastic material at the back of the brick and the opening thereof receiving the plastic material.

In testimony whereof I affix my signature.

CHARLES L. STUBBS.
